CARD RACK

Roy R. Smith and Dyle E. Williams, Kansas City, Mo.; said Smith assignor to said Williams

Application February 1, 1956, Serial No. 562,736

7 Claims. (Cl. 40—72)

This invention relates to card holders and is particularly adaptable for use in laundry call offices and the like whereby a card record is maintained for each customer.

The principal object of the present invention is to provide a card holder of this character having a plurality of clips or holders forming pockets for holding the cards, and particularly the arrangement of the clips and shaping thereof for providing a spring tension on the cards to hold the cards in the pockets and removability of the clips from the rods of the holding frame.

Other objects of the present invention are to provide a card holder of this character having clips forming pockets for the holding of the cards constructed so as to exert a pressure on the card to resiliently retain the cards therein; to provide a frame adapted to accommodate a plurality of holders or clips for holding the cards; to provide means for rotatably mounting the frame on a support; to provide holders for the cards adapted to nest one within the other so as to retain cards on each side of the frame member to provide the rack with a space for advertising indicia, and to provide a device of this character simple and economical to manufacture.

In accomplishing these and other objects of the present invention, I have provided improved details of structure the preferred forms of which are illustrated in the accompanying drawings, wherein:

Fig. 1 is a fragmentary perspective view of a plurality of frame members mounted on a rotatable support showing the clips or trays for holding the cards mounted in the racks.

Fig. 2 is an elevational view of one of the frames with the trays or clips mounted therein and particularly illustrating the horizontal rods for mounting the clips and with parts broken away to better illustrate the invention.

Fig. 3 is an enlarged perspective view of one of the clips or trays.

Fig. 4 is a cross-sectional view through the clip taken on a line 4—4 (Fig. 3).

Fig. 5 is a transverse-sectional view through a portion of the frame and clip particularly illustrating the mounting of the clips on the frame.

Referring more in detail to the drawings.

1 designates a card holder embodying the features of my invention comprising, a rotatable support 2 for a plurality of frames 3 pivotally mounted on the support.

The frames 3 consist of parallel vertical side arms or members 4 and 5 and ends 6 and 7. The respective ends of the side arm 4 have enlarged portions 8 and 9 providing on its respective ends trunnions 10 and 11 so as to pivotally mount the frame in openings 12 and 13 of upper and lower spaced plates 14 and 15 mounted upon a rod 16 forming the supporting member 2 at both the top and bottom as best illustrated in Fig. 1 so as to provide access to either side of the frame by pivoting said frame.

2

Any number of frames may be utilized as desired and each frame is provided with a plurality of spaced rods or pegs 17 extending horizontally inwardly from the side arms 4 and 5, each adapted for mounting a clip 18 providing a tray or pocket for cards 19 (Fig. 5).

The clips or card holders 18 are adapted to be mounted on the horizontally extending rods 17 and are preferably formed of a single sheet of material bent as at 20 (Fig. 3) to form upwardly extending legs 21 and 22.

Adjacent the bent portion 20 of the holder and spaced inwardly from the ends thereof the legs 21 and 22 are struck inwardly forming bosses as indicated at 23 to provide a pocket 24 for the horizontal rods 17 to retain the holders thereon. I preferably provide the bosses on each leg of the clip near the end thereof as illustrated in Fig. 3. The respective legs 21 and 22 of the holders are inclined outwardly slightly as indicated at 25 and then inwardly to form a narrow throat 26 between the respective legs and the outer ends are bent outwardly as indicated at 27 providing a pocket 28 for the cards 19 and to provide a spring tension on the holder to provide pressure on the cards to retain the cards therein. The clips or holders are preferably made of spring steel or similar metal although other materials may be adaptable for my purpose.

When the respective holders are placed on the rods as illustrated in Figs. 2 and 5 they will be nested one within the other and the spring action on the holders will cause the inside thereof, near the throat portion, to engage the outside of the holder next thereabove as indicated at 29, Fig. 5, thus exerting tension on the cards therein as indicated at 30. The bosses 23 will retain the holders on the horizontal rod but they may be removed therefrom by tensioning the legs of the clips outwardly.

Index tabs or cards 31 may be provided for insertion in the clips and provided with alphabetical indicia as indicated at 32 (Fig. 2).

The clips or card holders are placed on the frame 3 by placing same on the topmost horizontal rods 17 and then each one consecutively mounted to the next below rods, the lowermost horizontal rod being spaced from the bottom bar 6 a sufficient distance to allow insertion of the last holder thereover.

45 5 Integrally formed with the top of the side arm 5 of the frame 3 is a rod or bar 34 which is rounded upwardly toward the center and downwardly to connect with the enlarged portion 9 of side bar 4 as illustrated in Fig. 2 forming a space 35 between the rod 34 and the upper end of rod 7 of the frame 3. A plate 36 for advertising indicia or the like has its respective side edges 37 and 38 secured to the rods 7 and 34 by bending the edges therearound also as illustrated in Fig. 2, or by other suitable means.

55 6 In operation of a device constructed and assembled as described the cards 19 may be inserted on each side of the frame 3 in the holders or pockets and extend above the top edge of the holder a sufficient distance 60 to allow the name on the card to be viewed as shown at 33 in Fig. 5. The card will extend to substantially the top edge of the next above holder. The cards are placed on each side of the frame and by pivoting the frame either side may be viewed and rotation of the support will bring any frame member immediately to the operator's view.

70 It will be obvious from the foregoing that I have provided an improved clip or holder for cards on a framework structure which will provide spring tension thereon to retain the cards in the pockets on either side of the framework structure.

What we claim and desire to secure by Letters Patent:

1. In a card holding device including a rotatable support, a frame pivotally mounted on said rotatable support, said frame having spaced horizontal cross members therein, and card holding members removably arranged on said cross members, said holding members nesting one within the other and forming pockets for the cards and exerting pressure on the cards for retaining the same in the pockets.

2. In a card holding device including a rotatable support, a frame pivotally mounted on said rotatable support, said frame having spaced vertical side members, a plurality of rods extending inwardly from the side members, and card holding members removably arranged on said rods, said holding members nesting one within the other and forming pockets for the cards and said holding members exerting tension on the cards for retaining the same in the pockets.

3. In a card holding device including a rotatable support, a frame having vertical side arms, spaced rods on said side arms and extending inwardly thereof rods, trunnion means for pivotally mounting the frame on said rotatable support, substantially U-shaped card holding members having side arms removably arranged on said rods, said holding members forming pockets for the cards and the arms of said U-shaped holding members exerting pressure on the card for retaining the same in the pockets, the top of said frames including space for advertising indicia.

4. In a card holding device including a rotatable support and a plurality of frame members having cross rods therein and trunnions for pivotally mounting the frame on said rotatable support, a substantially U-shaped clip including legs members forming pockets for said cards, said clip having means near the U-shaped portion for retaining said clip on said rods and the legs of said U-shaped clip exerting pressure on the card for retaining the same in the pockets.

5. In a card holding device including a support and a plurality of frame members having cross rods therein

and trunnions adapted to pivotally mount the frames on a rotatable support, a substantially U-shaped clip including leg members forming a pocket for said cards, said clip having bosses near the bend of the U-shaped portion for retaining said clip on said rods and the legs of said U-shaped clip being bent outwardly from the U-shaped portion and inwardly forming a throat portion for exerting pressure on the card for retaining the same in the pocket.

6. In a card holding device including a support and a plurality of frame members having spaced rods therein and trunnions adapted to pivotally mount the frames on said rotatable support, a substantially U-shaped clip including leg members forming a pocket for said cards, said clip having bosses near the U-shaped portion for retaining said clip on said rods and the legs of said U-shaped clip being bent outwardly from the bend of the U-shaped portion and inwardly forming a throat portion for exerting pressure on the card for retaining the same in the pocket, the outer portion of said legs being turned outwardly to facilitate entry of the cards into the pocket of the clip, and alphabetical indicia cards spaced vertically in said clip members for ready reference to the cards therein.

7. In a card holding device including a support, a panel having spaced side arms swingable on the support, a plurality of spaced rods integrally formed on the side arms extending horizontally inwardly from said side arms, and resilient clip members for holding the cards mounted on said rods nesting one within the other, said clip members forming pockets for the cards and exerting pressure on the cards for retaining the same in the pockets.
